ABSTRACT: The invention provides storage-stable aqueous isotonic saline suspensions containing mammalian blood platelets glucose, magnesium chloride, and certain prostaglandins. The hemostatic function of the platelets is preserved in these suspensions.

STORAGE-STABLE HEMOSTATIC TRANSFUSION
SUSPENSIONS OF BLOOD PLATELETS, GLUCOSE,
MAGNESIUM CHLORIDE AND CERTAIN
PROSTAGLANDINS

BACKGROUND OF THE INVENTION

A crude mixture, called prostaglandin, was reported by von Euler, Arch. Exp. Path. Pharm. Abs. 175-78 (1934); 181 (1936); J. Physiol. 72,74 (1931); 81,102 (1934); 84,21 (1935); 88,213 (1936); and Klin. Wschr. 14, 1182 (1935). More recently essentially pure crystalline PGF (PGF₁ or PGF_{1α}) has been isolated, British Pat. No. 851,827 and Acta Chemica Scandinavica 14, 1693 (1960). Microbiological conversions of unsaturated fatty acids with mammalian glandular tissue are described in U.S. Pat. Nos. 3,290,226 and 3,296,091. In the latter patent PGF (PGF₁ or PGF_{1α}) is designated as 7-[3α, 5α-dihydroxy-2-(3-hydroxy-1-octenyl)-cyclopentyl]-heptanoic acid.

The PGF-type prostaglandins are characterized by the presence of the hydroxyl group at the five-position in the cyclopentane ring. The designation PGF_{1α} shows the configuration of the hydroxyl at the five-position. Various other members of the PGF-type are known and are named either systematically or in terms of their relationship to PGF. Illustrative thereof are PGF_{2α} or 7-[3α,5α-dihydroxy-2-(3-hydroxy-1-octenyl)-cyclopentyl]-5-heptenoic acid, PGF_{3α} or 7-[3α,5α-dihydroxy-2-(3-hydroxy-1,5-octadienyl)-cyclopentyl]-5-heptenoic acid, and dihydro PGF_{1α} or 7-[3α, 5α-dihydroxy-2-(3-hydroxyoctyl)-cyclopentyl]-heptanoic acid. Details of preparations from available materials are disclosed for dihydro PGF_{1α}, PGF_{2α}, and PGF_{3α} in Biochimica and Biophysica Acta, 84, 707 (1964), and for PGF_{1α} in U.S. Pat. No. 3,069,322. Bergstrom, Carlson and Weeks, Pharmacological Reviews, Vol. 20, No. 1, P. 1 (1968) review "The Prostaglandins."

In U.S. Pat. No. 3,290,226 PGE compounds are described including PGE₁, PGE₂ and PGE₃. The PGE Series is characterized by the presence of the keto group at the five-position in the cyclopentane ring. More recently, Ramwell et al., "Prostaglandins" in Progress in the Chemistry of Fats and other Lipids, Vol. 9 edited by R. Holman, pp. 73-115, Pergamon Press, Oxford, 1967 refer to prostaglandin PGE₁ as 11α, 15(S)-dihydroxy-9-oxo-13-trans-prostenoic acid, PGE₂ as 11α, 15(S)-dihydroxy-9-oxo-5-cis,13-trans-prostadienoic acid and PGE₃ as 11α,15(S)-dihydroxy-9-oxo-5-cis,13-trans, 17-cis-prostatrienoic acid.

PGE₁ 15-formate is prepared as follows: A solution of sodium carbonate (50 mg.) in 7.5 ml. of dry formic acid is added to 250 mg. of PGE₁. This mixture is stirred under nitrogen at 25° C. for 2 hours. The reaction mixture is evaporated under reduced pressure. Benzene is added to the residue and the mixture is again evaporated under reduced pressure. The residue is then chromatographed on 50 g. of silica gel (acid washed to pH 4; 100-200 U.S. mesh; Mallinckrodt Silicar CC-4), eluting with 2.5 l. of a gradient of 25 to 75 percent ethyl acetate-isomeric hexane mixture (Skellysolve B), and collecting 100-ml. fractions. Eluate fractions 9, 10, and 11 are combined and evaporated to dryness under reduced pressure to give 99 mg. of PGE₁ 15-formate. 8-iso-PGE₁ is described by Daniels, et al., J. Am. Chem. Soc. 90, 5894 (1968); dl-8-Iso-PGE₁, methylester is described by Schneider et al., J. Am. Chem. Soc. 90, 5896 (1968); and 11-dehydro-PGE_{1α} is described by Lands et al., J. Biol. Chem. 243, 4104 (1968).

Excepting PGE₃, these prostaglandins are to be construed as including optically active compounds of the natural configuration and racemic compounds. These compounds are known in the art or are available by methods known in the art. See U.S. Pat. No. 3,296,091; Rec. Trav. Chim. 85, 1233 (1966), Ibid. 87, 461 (1968); J. Am. Chem. Soc. 90, 5895 (1968). For the racemic compounds, see, for example, Chemical Communications, pp. 303-305 (1969).

Pharmaceutically acceptable salts for example, those of alkali metals and alkaline earth bases, such as the sodium, potas-

sium, calcium and magnesium salts; those of ammonia or a basic amine such as mono-, di-, and triethyl amines, benzylamine, heterocyclic amines such as piperidine and morpholine, and amines containing water-solubilizing or hydrophilic groups such as triethanolamine and phenylmonoethanolamine are disclosed in U.S. Pat. No. 3,296,091. Carboxylate esters such as methyl, ethyl, cyclohexyl and the like having no more than eight carbon atoms are formed by the usual methods, e.g., reaction with diazomethane or similar diazohydrocarbons as in U.S. Pat. No. 3,296,091.

Biological studies of the prostaglandins, for example, actions on smooth muscle, reproductive system, nervous system, cardiovascular system, and relationship to lipid and carbohydrate metabolism, and miscellaneous effects are summarized by Bergstrom et al.; "The Prostaglandins: A Family of Biologically Active Lipids," Pharmacological Reviews, Vol. 20, No. 1, P. 1 et sequitur, 1968, The Williams and Wilkins Company.

Blood platelets when stored for a few hours, and then infused, lose most of their ability to perform the hemostatic function. Consequently, all thrombocytopenias (congenital as well as drug-induced) must be treated with freshly prepared platelet suspensions. The instability of the physiological properties of platelets results in total waste of unused platelet suspensions and also presents a major problem in the treatment of thrombocytopenias. Inhibition of platelet aggregation by some prostaglandins, including PGE₁, has been demonstrated in various investigations. Kloeze, J., Nobel Symposium 2, Prostaglandins, Ed. S. Bergstrom and B. Samuelson, pp. 241-252. Almquist and Wiksell, Stockholm (1967). Emmons, P. R., Hampton, J. R., Harrison, M. J. R., Honour, A. J., and Mitchell, J. R. A., Brit. Med. J., 2, 468 (1967). Chandrasekhar, N., Blood, 30, 554 (1967). However, until the present invention, storage-stable suspensions of platelets both human and animal were not available.

SUMMARY OF THE INVENTION

This invention relates to the preservation of the hemostatic function of blood platelets. More specifically, it relates to storage-stable aqueous suspensions of mammalian blood platelets, for example, human and animal such as rabbit, rat, and monkey. The aqueous suspensions consist essentially of said platelets and a prostaglandin selected from the group consisting of PGE₁; PGE₁, 15-formate; 8-Iso-PGE₁; dl-8-Iso-PGE₁, methylester; and 11-dehydro-PGE_{1α}.

The aqueous suspensions of the platelets are preferably in the form of platelet-rich plasma or an aqueous suspension in 0.9 percent NaCl. The amount of prostaglandin for preservation of the hemostatic function of the platelets is within the nontoxic effective range from about 0.025 ug./ml. to about 1.0 mg./ml.

Additional ingredients complementing the preservative action of the prostaglandin component are glucose from about 1 to about 2 mg./ml. and from about 2.5 to about 10 milliequivalents of Mg in the form of magnesium chloride. In the suspensions the hemostatic activity of the platelets is preserved permitting their use in clinical conditions such as idiopathic thrombocytopenia and drug-related thrombocytopenia sometimes accompanying therapy with, for example, chloramphenicol, mustard-type cytotoxic agents, and cobalt treatments. Normally the human platelet count is from about 300,000 to about 500,000 per ml. In severe thrombocytopenia it may be depressed to about 50,000 per liter or lower necessitating infusion of 5 to 6 liters of preserved platelet suspension containing the effective nontoxic amount of prostaglandin.

DESCRIPTION OF THE PREFERRED EMBODIMENTS

A model system involving a decrease in the number of platelets in rats is used to show the storage stability of blood platelets in combination with the prostaglandin component.

Four groups (12 rats/group) of mature male Sprague-Dawley rats are X-irradiated at 100 R, 200 R, 300 R or 400 R. Three rats each from the four groups are sacrificed on the 5th, 7th, 9th or 11th day following X-irradiation, to obtain citrated blood samples for determination of platelet counts (Coulter counter). All groups develop maximum thrombocytopenia on the 9th day, after which the platelet counts show a gradual increase. Rats which receive the maximum X-irradiation (400R) show the maximum thrombocytopenia.

Platelet counts of Platelet-Rich Plasma obtained from Rats X-Irradiated at four different levels (three animals per group; Mean Counts expressed as $\times 10^3/\text{mm}^3$)

No. of days following X-Irradiation	X-Irradiation Level			
	100 R	200 R	300 R	400 R
Day 5	1,964 $\pm$ 80	1,487 $\pm$ 33	1,151 $\pm$ 162	1,242 $\pm$ 161
Day 7	1,809 $\pm$ 73	1,372 $\pm$ 69	1,209 $\pm$ 52	985 $\pm$ 140
Day 9	1,127 $\pm$ 137	880 $\pm$ 87	593 $\pm$ 97	471 $\pm$ 205
Day 11	1,816 $\pm$ 232	1,321 $\pm$ 91	1,174 $\pm$ 269	927 $\pm$ 95

Three groups (12 rats/group) of mature male Sprague-Dawley rats are X-irradiated at 300 R. On the 6th day following X-irradiation, fresh platelet-rich plasma (PRP) is collected by centrifuging citrated blood (from another set of nonirradiated Sprague-Dawley rats) at 1200 r.p.m. for 10 minutes. One aliquot of the PRP is incubated with PGE₁ (100 ug./ml.) for 48 hr. at 5°. Another aliquot of PRP is incubated with an equal volume of physiological saline (positive control). On the 8th day following X-irradiation, another sample of fresh PRP is obtained. One group of 12 rats (negative controls) is given tail vein injections of the freshly prepared PRP (four injections of 2 ml. each, equally spaced within 8 hr.). Another group (positive controls) is given similar injections of saline-incubated PRP and the third group (experimental) is given PGE₁-incubated PRP. All rats are sacrificed 24 hr. after infusion and the platelet aggregation (collagen-induced) of their PRP samples is determined using the Aggregometer. Results show that negative controls with fresh platelets give the maximum aggregation values and the positive control group with saline-incubated PRP shows the poorest aggregation values compared to the positive control group, indicating that PGE₁ preserves the hemostatic function of stored platelets.

Platelet-Aggregation in Thromocytopenic Rats after PRP-Infusion

Treatment	Collagen-Induced Aggregation in 5 Min.
Negative Control	8.1 $\pm$ 0.7
Positive Control	3.0 $\pm$ 0.5
Experimental (PGE ₁ -incubated PRP)	3.7 $\pm$ 0.8

INHIBITION OF PLATELET AGGREGATION

Materials and methods are available for determining the ability and effective amount of the prostaglandins for inhibition of mammalian platelet aggregation.

All prostaglandins are dissolved in 95 percent ethyl alcohol

to yield a 10 mg./ml. solution. Acidic solutions are then diluted to 1 mg./ml. concentration, with a 0.2 mg./ml. sodium carbonate solution; esters are diluted to a concentration of 1 mg./ml. with 0.9 percent sodium chloride. Subsequent dilutions of all prostaglandins are accomplished with 0.9 percent sodium chloride; freshly prepared solutions only are used in the experiments. Platelet-rich plasma (PRP) is used as the source of platelets. Freshly drawn citrated blood samples from adult male Sprague-Dawley rats (Spartan strain) are centrifuged at 1200 r.p.m. for 10 min. to obtain rat PRP.

Three aggregation inducers are used: (1) 0.25M calcium chloride solution; (2) 50 mg./ml. adenosine diphosphate solution (ADP) freshly prepared using Ringer's solution; (3) collagen suspension made up in Tyrode solution without calcium.

Two methods are employed to measure platelet aggregation parameters: a modification of Chandler's visual technique using a revolving plastic loop and a photo-optical method using an Aggregometer (Chronolog Corporation, Broomall, Pa.). For the Chandler's loop method, 0.8 ml. volume of PRP

is taken up in a plastic loop (Transflex No. 8, 3M Company), 0.1 ml. of a 1 mg. per ml. solution of the prostaglandin is added to the plasma and the loop is rotated at 12 r.p.m. for 1 minute to assure proper mixing. An 0.1 ml. volume of 0.25M calcium chloride is then injected onto the plasma layer at one end of the loop and three stop watches and the loop are started simultaneously. Three end points which occur in succession are recorded: (1) aggregation of platelets visible to the naked eye (VA); (2) appearance of snowstormlike platelet clumps (SS); and (3) a well-packed platelet disc or head at

one end of the plasma surface (PH). Similar experiments are carried out using physiological saline in place of prostaglandin solution, to obtain control values. If VA obtained with prostaglandin is greater than 10 seconds from that of the controls, successive dilutions of prostaglandins are made and tested. The lowest concentration of prostaglandin that prolongs VA for more than 10 seconds is tested on three separate rat PRP samples and the mean and standard error of VA, SS and PH are recorded.

Platelet aggregation phenomenon induced by ADP and collagen is studied in the Aggregometer. Freshly obtained rat PRP (0.8 ml.) is mixed with 0.1 ml. of the prostaglandin solution in an Aggregometer cuvette for 1 minute. 0.1 ml. of the collagen suspension is pipeted into this cuvette to induce aggregation. Platelet aggregation/adhesion that takes place in the cuvette produces changes in optical density which are recorded on a Bausch and Lomb VOM 6 recorder. The height of the curve recorded is taken as the aggregation index. Identical experiments are done using PRP from control animals also. If the aggregation index for the experimental samples is less than 80 percent of that of the controls, prostaglandin (at that particular concentration) is considered active.

All prostaglandins are initially tested in the Chandler's loop to determine the lowest concentration that is active. The compound is again tested in the Aggregometer at the lowest active concentration, against ADP and collagen.

I claim:

1. A storage-stable aqueous suspension in isotonic saline with effective complementary hemostatic activity preserving concentrations of glucose and magnesium chloride for transfusion consisting essentially of mammalian blood platelets and a prostaglandin selected from the group consisting of PGE₁; PGE₁-15 formate; 8-Iso-PGE₁; dl-8-Iso-PGE₁; methylester; and 11-dehydro-PGF₂ α , the amount of the prostaglandin being within the nontoxic effective range from about 0.025 ug./ml. to about 1 mg./ml. of the suspension.
